No. 826,514.

PATENTED JULY 17, 1906.

S. L. G. KNOX.

LOWER TUMBLER FOR DREDGES AND THE LIKE.

APPLICATION FILED SEPT. 20, 1905.

Fig. 1.

UNITED STATES PATENT OFFICE.

SAMUEL LIPPINCOTT GRISWOLD KNOX, OF MILWAUKEE, WISCONSIN,
ASSIGNOR TO THE BUCYRUS COMPANY, OF SOUTH MILWAUKEE,
WISCONSIN, A CORPORATION OF WISCONSIN.

LOWER TUMBLER FOR DREDGES AND THE LIKE.

No. 826,514.

Specification of Letters Patent.

Patented July 17, 1906.

Application filed September 20, 1905. Serial No. 279,368.

To all whom it may concern:

Be it known that I, SAMUEL LIPPINCOTT GRISWOLD KNOX, a citizen of the United States, residing at Milwaukee, county of Milwaukee, State of Wisconsin, have invented certain new and useful Improvements in Lower Tumblers for Dredges and the Like; and I do hereby declare the following to be a full, clear, and exact description of the invention, such as will enable others skilled in the art to which it appertains to make and use the same.

This invention relates to dredging apparatus, and particularly to the lower tumblers over which the chain with the dredging-buckets passes.

As ordinarily constructed, the lower tumblers referred to have been polygonal in shape, the flat peripheral faces terminating at their lines of intersection with adjacent faces. Where the buckets extend to a considerable extent over the rear or trailing edge of the faces, and this is usually the case in dredging apparatus, the drag of a following upon a preceding bucket tends to break the back of the preceding bucket across the edge formed at the intersection of two adjacent faces as the buckets pass successively over the tumbler. While this tendency does not ordinarily result in an actual breaking in two of the bucket, yet the wearing to the buckets upon the edge soon wears holes in the backs of the buckets. This wearing action is increased by the hard character of the material, usually manganese steel, which is employed at the junctions of the faces to prevent their wearing away.

The object of the invention is to prevent the buckets from drawing across the edges of the peripheral faces of the tumbler, as has been described, thereby doing away with the tendency to break the bucket and also with the wearing of holes in the bucket-backs, as has been mentioned. This is accomplished by providing a projection at an edge of each face of the tumbler, which projection overhangs an adjacent face.

A further object of the invention is to provide an improved construction of tumbler, as will be hereinafter set forth.

The invention can be best explained in connection with the accompanying drawings, of which—

Figure 1 is a plan view of a tumbler embodying the invention with a portion of the chain in dotted lines sufficient to show its relation to the tumbler, and Fig. 2 is a section of a tumbler with flange omitted on the line *a-b* of Fig. 1 looking in the direction of the arrow. A portion of a bucket-chain is applied thereto, and certain portions of the chain are shown by dotted lines.

Upon a suitable shaft *A* is mounted a spider *B*, of suitable construction. This spider is shown as keyed to the shaft, while the shaft may be mounted in any suitable bearings. Upon the periphery of the spider are formed a plurality of plane faces *C*, each of which has a projection *D* from its trailing edge which overhangs an adjacent face. The direction of rotation of the tumbler is indicated by the arrow in Fig. 2.

Each of the faces *C* may comprise two elements 1 and 2, which are axially and oppositely inclined, so as to form a wedge-shaped face, and thus an opening 3 is provided between the elements at their diverging ends 4 5 at the wide end of the surface, so that the converging ends 6 7 of the elements of an adjacent face (and the narrow end of the corresponding face) may pass through the opening 3. The converging ends 6 7 extend beyond the surface of the adjacent face, so that the overhanging projection *D* is formed as before described. At the sides of the tumbler are provided flanges 8 9 to guide the chain upon the tumbler, as is well understood. The chain comprises a plurality of links 10, each comprising a bucket 11, of suitable form. The chain may be, for instance, constructed as shown in the patent to me granted May 16, 1905, No. 790,211. Reference to this patent will show that at one end of the link is a double eye, while at the other is a single eye, and the various links are adapted to be connected together by inserting a single eye of one link between the double eyes of the other link and then inserting a pin. In the usual construction of lower tumbler before referred to the back 12 of a bucket would

tend to become broken across the line 13 and wear of the bucket, as before adverted to, would be occasioned. The projection D, however, on the edge of each face supports 5 the drag of a succeeding link upon its preceding one, and thereby does away with the objectionable consequences noted.

By reference to Fig. 1 it will be seen that the end of the link having the single eye 14 is 10 supported by the projection D, composed in this case of the ends 6 7 of the surface elements, while the double eye 15 of the succeeding link straddles that projection, sufficient clearance being provided on both sides 15 to accommodate the double eye.

The spider B is usually of cast-iron, and to increase the wearing qualities the faces C are generally formed by securing plates 16 of manganese steel to the spider by riveting, as 20 shown, or other suitable means.

While the invention has been illustrated in what is considered its best application, it is to be understood that it may be embodied in other constructions and should not, therefore, 25 be limited to that shown.

Having thus described the invention, what I claim as new, and desire to secure by Letters Patent, is—

1. The combination with a bucket-chain, 30 of a tumbler at the lower end thereof, having a plurality of peripheral faces, each of said

faces having a projection overhanging an adjacent face.

2. The combination with a bucket-chain, of a tumbler at the lower end thereof, having 35 a plurality of peripheral faces, each of said faces having a projection from its trailing edge overhanging an adjacent face.

3. A tumbler having a plurality of peripheral faces, each comprising two oppositely 40 axially inclined elements.

4. A tumbler having a plurality of peripheral wedge-shaped faces, the narrow end of each face being adjacent to and projecting beyond the broad end of an adjacent face. 45

5. A tumbler having a plurality of peripheral wedge-shaped faces, the narrow end of one face entering an opening in the broad end of an adjacent face and projecting beyond the surface of the last-mentioned face. 50

6. A tumbler having a plurality of peripheral faces, each comprising two oppositely axially inclined elements, the converging ends of said elements passing between and projecting beyond the diverging ends of the 55 elements of an adjacent face.

In testimony whereof I have affixed my signature in presence of two witnesses.

SAMUEL LIPPINCOTT GRISWOLD KNOX.
